*Primary Examiner—Philip S. Hyder**Assistant Examiner—C. Tuttle**Attorney, Agent, or Firm—Edward S. Podszus***[57]****CLAIM**

The ornamental design for a hair forming appliance, as shown and described.

DESCRIPTION

FIG. 1 is a front and right side perspective view of a hair forming appliance, showing my new design;

FIG. 2 is a front view of the appliance of FIG. 1;

FIG. 3 is a right-side view of the appliance of FIG. 2;

FIG. 4 is a left-side view of the appliance of FIG. 2;

FIG. 5 is a top plan view of the appliance of FIG. 2; and,

FIG. 6 is a bottom plan view of the appliance of FIG. 2.

The undisclosed rear end of the appliance forms no part of the claimed design.
